UNITED STATES PATENT OFFICE.

EDWARD ALBERT FARR, OF MERIDEN, CONNECTICUT.

DESIGN FOR A CRUMB-TRAY.

51,676.

Specification for Design.

Patented Jan. 8, 1918.

Application filed September 24, 1917. Serial No. 193,052. Term of patent 7 years.

To all whom it may concern:

Be it known that I, EDWARD A. FARR, a citizen of the United States, residing at Meriden, county of New Haven, State of Connecticut, have invented a certain new, original, and ornamental Design for Crumb-Trays, of which the following is a specification, reference being had to the accompanying drawings, forming part hereof.

The figure is a plan view of a crumb tray showing my new design, the same consisting of the general shape or configuration of the article shown.

I claim:

The ornamental design for a crumb tray, as shown and described.

EDWARD ALBERT FARR.
